UNITED STATES PATENT OFFICE.

OWEN B. BLAKESLEE, OF BURLINGAME, KANSAS.

JOINT-LOCK FOR STOVE-PIPES.

SPECIFICATION forming part of Letters Patent No. 368,703, dated August 23, 1887.

Application filed December 20, 1886. Serial No. 222,097. (No model.)

To all whom it may concern:

Be it known that I, OWEN B. BLAKESLEE, a citizen of the United States, residing at Burlingame, in the county of Osage and State of 5 Kansas, have invented certain new and useful Improvements in Joint-Locks for Stove-Pipes; and I do declare the following to be a full, clear, and exact description of the invention, such as will enable others skilled in the art to which it 10 appertains to make and use the same, reference being had to the accompanying drawings, and to the letters and figures of reference marked thereon, which form a part of this specification.

The special object of the invention is to lock 15 together sections of stove-pipe, so that they will always remain as placed.

The invention will first be described in connection with the drawings, and then pointed out in the claim.

20 Figure 1 of the drawings is a side elevation of two sections of stove-pipe locked together by my invention. Fig. 2 is a detail view in perspective of my locking-piece.

In the drawings, A A represent two pieces 25 of stove-pipe belonging to different sections; B, my locking-piece.

My locking-wire or metallic strip B is made

somewhat like the old reaping-hook, being provided with the curved body b' , and the arm b'' arranged at an angle thereto. In the stove-pipes are made two holes, $a a$, in each, those of one pipe registering with those of the other, so that the point b of the locking-piece may pass through the four holes and have the arm resting on the outer section. The strain produced by the weight of pipes being in a line across the curved body b' , will effectually hold the lock-piece in place.

Having thus described my invention, what I claim as new and of my invention is—

The combination, with two pipes or plates having each two corresponding holes, $a a$, of a lock-piece having the body b' , curved to conform to the arc of the circle, of which the point b forms a part, and the straight arm b'' , whereby 45 sections of pipe may be joined together, substantially as shown and described.

In testimony whereof I affix my signature in presence of two witnesses.

OWEN B. BLAKESLEE.
